ATTORNEY

UNITED STATES PATENT OFFICE.

LEWIS WARRINGTON CHUBB, OF EDGEWOOD PARK, PENNSYLVANIA, ASSIGNOR TO
WESTINGHOUSE ELECTRIC & MANUFACTURING COMPANY, A CORPORATION OF
PENNSYLVANIA.

CONTROL APPARATUS.

Original application filed June 9, 1919, Serial No. 302,793. Divided and this application filed September 28, 1921. Serial No. 503,912.

To all whom it may concern:

Be it known that I, LEWIS WARRINGTON CHUBB, a citizen of the United States, and a resident of Edgewood Park, in the county of Allegheny and State of Pennsylvania, have invented a new and useful Improvement in Control Apparatus, of which the following is a specification, this application being a division of my application Serial No. 302,793, filed June 9, 1919.

My invention relates to control apparatus and it has special relation to the variation of resistance in liquid rheostats.

One object of my invention is to provide a liquid rheostat wherein means are provided for actively utilizing a relatively large proportion of the electrode surfaces under high-voltage conditions of the rheostat, whereby arcing in the rheostat, when an induction motor or other device to be governed is started into operation, is avoided.

Another object of my invention is to provide a moving column of electrolyte between the electrodes, together with means for varying the length or cross-section of said column to change the resistance of the rheostat.

Other more specific objects of my invention will become evident from the following detailed description, taken in conjunction with the accompanying drawings, wherein—

Figure 1 is a diagrammatic view, partly in side elevation and partly in section, of a liquid rheostat designed in accordance with my invention; and

Fig. 2 is a cross-sectional view of a modified form of liquid rheostat for accomplishing similar results.

Referring to Fig. 1 of the drawing, the apparatus that is illustrated comprises a suitable tank or reservoir 40 having a discharge opening 41 with which suitable pumping apparatus is associated to supply a continuous flow of electrolyte through the manifold or spreader 33. A description of pumping apparatus suitable for this type of liquid rheostat is set forth in the above identified parent application filed June 9, 1919, Serial No. 302,793.

A plurality of pairs of plates or electrodes 42 are suitably located in the rheostat, and alternate pairs are electrically connected to the conductors 14a and 26a, respectively. Curtains or pieces of cloth 43 and 44, such

as canvas, are attached to the lower ends of the plates comprising the respective pairs. Consequently, the column of liquid between the plates 42 is carried downwardly to the bottom of the tank, as indicated by the solid arrows, between the curtains 43 and 44, which thus guide the column of liquid. To ensure that the plate area is maintained at the full active value, or, in other words, that the entire inner surfaces of the plates 42 are at all times utilized, the curtains 43 and 44 are caused to approach each other, a certain distance below the edges of the plates 42, to provide a constricted opening or pocket, which will ensure a complete column of electrolyte above the constricted section and, in particular, between the plates 42.

For the purpose of providing the above-mentioned constricted opening or pocket, the illustrated apparatus or any equivalent thereof may be employed. The method shown consists in placing rods 45 of wood or other insulating material along the outside of the curtains 43 and 44 at the plane where it is desired to begin the constriction, and the rods 45 are held in the proper relation to each other by means of rope or wire 46. Furthermore, if desired, similar ropes or wires 47 may be employed to join adjacent pairs of curtains and, if the ends of the ropes or wires are fastened to the tank walls, the complete set of curtains is maintained in the proper position to ensure the flow of substantially steady columns of electrolyte downwardly between the pairs of plates.

The initial path of the electric current is indicated by the dotted arrows in the left-hand half of Fig. 2, namely, from one conductor 26a downwardly between one pair of plates 42 and the corresponding curtains, along the moving stream near the bottom of the tank, and upwardly between the next set of curtains and plates to the other conductor 14a. In this way, a liquid path of initially high resistance is provided in the rheostat.

By raising the level of the electrolyte outside of the respective pairs of plates, by means of a valve for changing the size of the discharge opening 41, or in any other suitable manner, the outer surfaces of the electrodes are also rendered active. During

2
this process, the saturated curtains, although themselves non-conducting, serve to transmit the electric current from within one pair of curtains through the main body of 5 electrolyte to the column within the adjacent pair of curtains, as indicated by the dotted arrows. When the maximum level, represented by the dotted line, is reached in the rheostat, the electrodes are approximate- 10 ly immersed and a relatively low total resistance of the rheostat is provided.

In the modification just described, it will be noted that, under low-level and high-resistance conditions of the rheostat, substantially one half the plate area is active, whereas, under high-level and low-resistance conditions, practically the entire plate area is utilized. Under all conditions, therefore, a sufficiently large proportion of the elec- 20 trode surfaces is immersed to prevent the possibility of arcing at the electrodes.

In Fig. 2, the constriction in the curtains or cloths 48 and 49 that are attached to the lower ends of the electrodes 42 is placed considerably lower than is the case in Fig. 1. In this way a large column of water is provided, except near the bottom of the curtains. It will be understood that, in some cases, the structure illustrated in Fig. 2 will 30 be necessary to ensure a continuous filling of the space between the electrodes 42, particularly if they are of relatively great height.

I do not wish to be restricted to the specific structural details or arrangement of parts herein set forth, as various modifications thereof may be made without departing from the spirit and scope of my invention. I desire, therefore, that only such 40 limitations shall be imposed as are indicated in the appended claims.

I claim as my invention:

1. In a liquid rheostat, the combination with a plurality of electrodes, of a plurality

of non-conducting curtains hung from the 45 bottoms of said electrodes, and means for constricting the space between said curtains.

2. In a liquid rheostat, the combination with a plurality of electrodes, of a moving column of electrolyte between said electrodes, and a plurality of cloth curtains for constricting the sectional area of said column after leaving said electrodes.

3. In a liquid rheostat, the combination with a plurality of electrodes, said electrodes being arranged in groups having relatively the same potential, of a plurality of columns of electrolyte flowing between corresponding groups of said electrodes, and a tank for receiving said electrolyte. 55

4. In a liquid rheostat, the combination with a plurality of electrodes, said electrodes being arranged in groups having relatively the same potential, of a plurality of columns of electrolyte flowing between corresponding groups of said electrodes. 65

5. In a liquid rheostat, the combination with a plurality of electrodes, said electrodes being arranged in groups having relatively the same potential, of a plurality of columns 70 of electrolyte flowing between corresponding groups of said electrodes, and a plurality of non-conducting members supported by said electrodes.

6. In a liquid rheostat, the combination with a plurality of electrodes, said electrodes being arranged in groups having relatively the same potential, of a plurality of columns 75 of electrolyte flowing between corresponding groups of said electrodes, a plurality of non-conducting curtains hung from the bottoms of the electrodes, and means for constricting the space between said curtains. 80

In testimony whereof, I have hereunto subscribed my name this 21st day of September 1921.

LEWIS WARRINGTON CHUEB.
